[57] CLAIM

The ornamental design for a clip for keeping socks in pairs, as shown and described.

DESCRIPTION

FIG. 1 is a perspective view as seen from the top and front end of a clip for keeping socks in pairs showing my new design;

FIG. 2 is a side elevational view thereof, the opposite side being a mirror image;

FIG. 3 is a top plan view thereof, it being noted that the bottom plan is adorned with the same surface ornamentation; and,

FIG. 4 is a rear elevational view thereof.

FIG. 1

FIG. 2

FIG. 3

FIG. 4
